UNITED STATES PATENT OFFICE.

GEORGE W. FARRELL, OF AU SABLE FORKS, NEW YORK.

CARRIAGE-GEAR.

SPECIFICATION forming part of Letters Patent No. 417,480, dated December 17, 1889.

Application filed March 22, 1889. Serial No. 304,358. (No model.)

To all whom it may concern:

Be it known that I, GEORGE W. FARRELL, a citizen of the United States, residing at Au Sable Forks, in the county of Essex and State 5 of New York, have invented certain Improvements in Running-Gear for Vehicles, of which the following is a specification.

My invention has reference to the running-gear of vehicles; and it consists in the improved construction, hereinafter described and set forth, whereby a simple and efficient arrangement is provided that will readily and cheaply subserve the purpose designed and dispense with the necessity for a reach.

Other advantages are incident to my improvements, and will be fully detailed herein-after.

In the accompanying drawings, forming part of this specification, Figure 1 is a central longitudinal section of a vehicle embodying my improvements. Fig. 2 is a plan view of the same, and Fig. 3 is a longitudinal sectional view of a vehicle having a modified form of gearing.

The rear axle C and front axle D each have secured at each side of the respective centers side springs a , which are pivotally connected to said axles by means of clips a' . As shown in Fig. 1, each of said springs a is composed of a 25 distinct front and rear member, bent slightly semi-elliptical, its upper inner end being bent, as shown, to form a horizontal bearing portion for the attachment of the short blocks a^2 , upon which the body rests. These blocks 30 a^2 are preferably braced relative to each other by a transverse brace a^3 . At the front a metallic brace is employed, consisting of two downwardly-curved rods B, converging toward each other at their lower terminal portions, at which point they terminate in eyes 35 b , horizontally perforated for pivotal attachment to a clip c , secured to the front axle and to the head-block thereof. The upper separated ends of these rods B are likewise 40 provided with horizontally-perforated eyes abutting against the inner sides of the blocks a^2 , to which they are bolted adjacent to their forward ends, as indicated at E.

Brace-rods B' are secured to the rear axle

outside of the longitudinal plane of the 50 springs and blocks, and said rods B' incline forward and inward and carry at their upper ends horizontally-perforated eyes, each bolted on the outer face of the adjacent block, as shown at E.

From the description and illustration so far presented it will be quite clear that the running-gear set forth is of simple, inexpensive, and durable construction, and that a reach is entirely dispensed with. Another 60 advantage that ensues arises from the fact that the disposition of the braces is such that the springs are entirely relieved from the strain usually experienced when the wheel comes in contact with an obstruction.

In Fig. 3 the upper bent bearing portion of each of the spring members is absent, the plain ends of said springs being secured to the bottom of the blocks.

I claim—

1. The combination, in running-gear for vehicles, of the independent side springs connected to the independent blocks, as described, and adapted for attachment to the front and rear axles, and each composed of 75 two disconnected members, each separately connected to its block, together with the rear braces connected to the outer sides of said blocks, and front braces connected to the inner sides thereof and to the axle, whereby 80 the reach is dispensed with, substantially as set forth.

2. The combination, in running-gear for vehicles, of the independent side springs connected to the independent blocks, as de- 85 scribed, and adapted for attachment to the front and rear axles, and each composed of two disconnected members, each separately connected to its block, together with rear inclined braces connected to the outer side of 90 said blocks, and front inclined braces connected to the inner sides thereof and downwardly converging and connected to a central clip on the front axle, whereby the reach is dispensed with, substantially as set 95 forth.

3. The combination, in running-gear for vehicles, of the independent side springs

connected to the independent blocks, as described, and each consisting of two disconnected downwardly-curved members connected to the front and rear axles, respectively, and each having their inner end bent back upon itself to form a bearing portion, together with independent blocks and dis-

tinet front and rear braces, whereby the reach is dispensed with, substantially as set forth.

GEORGE W. FARRELL
